FIG. XXII.

FIG. XXII.

A diagram of a curved pipe with various points labeled with numbers. The pipe starts at point 59 on the left, curves upwards to point 75, then downwards to point 69. It then turns back upwards to point 51, then downwards to point 10. The pipe then turns back upwards to point 96, then downwards to point 56. Finally, it turns back upwards to point 50, then downwards to point 2. The numbers are arranged as follows: 59, 75, 69, 51, 10, 96, 56, 50, 2.

UNITED STATES PATENT OFFICE.

EDWARD WILLEY MARVEL, OF PHILADELPHIA, PENNSYLVANIA, ASSIGNOR, BY
MESNE ASSIGNMENTS, TO THE MOSLER LOCK COMPANY, OF COVINGTON, KEN-
TUCKY, A CORPORATION OF OHIO.

CHANGEABLE COMBINATION KEY LOCK.

Application filed January 5, 1922. Serial No. 527,063.

To all whom it may concern:

Be it known that I, EDWARD WILLEY MARVEL, a citizen of the United States, residing at Philadelphia, in the county of Philadelphia and State of Pennsylvania, have invented a certain new and useful Improvement in Changeable Combination Key Locks, whereof the following is a specification, reference being had to the accompanying drawings.

My invention relates to locks adapted for use in connection with safety deposit boxes and similar enclosures and of the general character described in Letters Patent of the United States 1,166,380 and 1,166,381 granted to me December 28, 1915, to wit, locks normally requiring the use of both a guard key and a main key to effect each opening movement of the lock.

Safety deposit boxes being successively leased to different parties to whom the lessor furnishes a main key adapted to open a given box when the lock thereof is partially operated by a guard key in the possession of the lessor; the lessees sometimes fail to return the main keys at the expiration of their leases and it is necessary to change the locks before again leasing them, in order to render the boxes secure against unauthorized use. Moreover, even if the lessees return the main keys at the expiration of their leases, it is desirable to change the locks whenever the lessees of the boxes are changed, to prevent the otherwise possible use of unauthorized duplicates of the keys which have been returned.

My present invention renders such a lock changeable as to the combinations of its tumblers, so that it may be adjustably set to be opened by different main keys. In the latter respect, my present invention is of the general character described in Letters Patent of the United States 1,145,870 granted to me July 6, 1915. However, my present invention differs from that disclosed in the last named Letters Patent, not only in the specific construction and arrangement of the mechanism of the main lock, but in the provision of an auxiliary key lock, in such correlation with the main lock, that it is necessary to unlock the auxiliary lock to permit the combination of the main lock to be changed.

Therefore, my present invention is advantageous in providing a lock of the character described with means whereby the combination controlled by the main key may be readily changed without removing the lock, or otherwise disturbing its mechanism, and while it remains subject to operation by the same guard key. In those respects, my present invention resembles that disclosed in my copending application Serial 349,939 for Letters Patent of the United States. However, my present invention differs from that disclosed in said application in that the auxiliary key lock above contemplated is entirely concealed within the casing of the main lock and operable through the guard key hole of the latter; and in that the fences engaging the main tumblers are mounted for rotary movement, whereas the fences in the invention disclosed in said application are mounted for rectilinear reciprocation; so that the present construction permits of a much more compact arrangement of the lock elements.

As hereinafter described, my invention includes a series of counterpart pivoted main tumblers, subject to operation by main keys, each of said tumblers having a sectoral series of gear teeth at its free end and being independently adjustable to different positions of arcual engagement with respect to a rotary fence; each of said fences being in the form of a gear wheel having a sectoral series of gear teeth arranged to mesh with the gear teeth on its tumbler; said fences having means continuously maintaining them in operative position, including a stationary stud shaft upon which they are pivoted, but said main tumblers being adapted to be simultaneously disengaged from their respective fences by shifting them, with the stud shaft upon which they are pivoted; that shaft being fixed in a reciprocatory change plate, normally prevented from moving, by the auxiliary lock; so that when said fences are thus disengaged, any one of a series of main keys may be inserted and turned to sweep said main tumblers into cooperative adjustment with respect to that key, and into reengagement with said fences, but in a correspondingly changed relation, to thereafter remain subject to

operation by that particular main key, until the combination to which said main tumblers have been thus adjustably set is again changed.

5 My present invention includes the various novel features of construction and arrangement hereinafter more definitely specified.

In said drawings: Fig. I is a front elevation of a lock conveniently embodying my 10 invention, with its locking slide bolt in locked position.

Fig. II is a rear elevation of the lock shown in Fig. I, with its locking slide bolt in locked position.

15 Fig. III is an elevation of the right hand end of said lock as shown in Fig. I, which is the left hand end of said lock as shown in Fig. II.

Fig. IV is a front elevation of said lock 20 shown in Figs. I to III inclusive, with its mechanism in the same locked position, but with the front cover plate removed to show the relative position of the elements of said mechanism which are normally concealed 25 by said plate.

Fig. V is a front elevation of said lock, 30 similar to Fig. IV, but showing the rotary key hub turned one-sixth revolution clockwise, which is the full extent of its movement by the guard key, preliminary to the unlocking movement of said slide bolt, by the main key for which the mechanism has been 35 adjusted. However, said key hub must be turned backward by the guard key to the position shown in Fig. IV, and said guard key withdrawn before said main key is inserted.

Fig. VI is a front elevation of said lock, 40 similar to Figs. IV and V, but showing said rotary key hub returned to the same position as in Fig. V, but by the main key for which it has been adjusted; so as to shift said locking bolt to its normal unlocked position, which is shown in Fig. VI.

45 Fig. VII is a front elevation of said lock, similar to Fig. VI, but with the auxiliary lock unlocked to permit the combination to be changed. Such change is effected by turning said rotary key hub, clock-wise, one-sixth revolution, from its locked position shown in Fig. I, but by means of the auxiliary lock key inserted in the guard key hole of said hub, to unlock the auxiliary lock; said hub being then returned anti-clock-wise, to the normal position shown in Fig. IV, by said auxiliary lock key, to permit the latter to be withdrawn; and said key hub is then turned one-half revolution, from its locked position shown in Fig. I, 50 to not only retract said locking bolt but withdraw the pivoted main tumblers aforesaid, to the position shown in Fig. VII, in which their sectoral series of gear teeth are disengaged from the sectoral series of gear teeth of the rotary fences aforesaid.

Fig. VIII is a front elevation of said lock, similar to Fig. IV, but with the combination of said tumblers changed by inserting a different main key in said rotary hub, 70 while the latter is in the position shown in Fig. VII, and turning it, anticlockwise, to sweep said main tumblers into cooperative adjustment with respect to that key, and re-engage them with said rotary fences, in the position shown in Fig. VIII; which is different from that shown in Figs. IV to VI inclusive. Fig. VIII also shows the auxiliary lock in its normal locked position as in Figs. I and IV to VI inclusive; so that Fig. VIII differs from Fig. IV only as to 75 the position of said main tumblers.

Fig. IX is a vertical sectional view of said lock, taken on the line IX, IX in Figs. I and IV.

Fig. X is a vertical sectional view of said lock, taken on the line X, X in Figs. I and IV.

Fig. XI is a plan sectional view of said lock, taken on the line XI, XI in Figs. I and IV.

Fig. XII is a plan sectional view, taken 90 on the line XII, XII in Fig. VII.

Fig. XIII is a side elevation of the guard key of said lock.

Fig. XIV is an elevation of the main 95 key to which said lock mechanism is adjusted when said main tumblers are in the position shown in Figs. IV to VI inclusive.

Fig. XV is an elevation of the different main key to which said lock mechanism is 100 adjusted when the main tumblers are in the position shown in Fig. VIII.

Fig. XVI is an elevation of the auxiliary 105 key, for the auxiliary lock which controls the combination changing mechanism.

Fig. XVII is an elevation of an auxiliary 110 key for the auxiliary lock of a different form from that shown in Fig. XVI; in illustration of the fact that my present invention is susceptible of variation in that respect; so that the same series of main keys may be used with respectively different auxiliary lock keys; the latter, of course, being adapted to cooperate with correspondingly different tumblers.

Fig. XVIII is a front elevation of the locking bolt.

Fig. XIX is a front elevation of the change plate.

Fig. XX is a front elevation of one of the partition plates, which separate the fences and main tumblers.

Fig. XXI is a front elevation of the auxiliary lock lever.

Fig. XXII is a front elevation of said lock, similar to Fig. VII, but on a larger scale, showing the auxiliary lock unlocked to permit the combination to be changed.

Fig. XXIII is a front elevation of said lock, similar to Fig. VIII, but on the same 130

scale as Fig. XXII, showing the combination changed by inserting a main key which is different from that with which the lock mechanism was set in the position shown in Fig. IX. It may be observed that Fig. XXIII differs from Fig. IV only as to the position of the main tumblers.

Fig. XXIV is a front elevation of the guard lever which is manipulated by said guard key shown in Fig. XIII; which lever has two arms, the longer arm serving as a 10 detent for the locking bolt, and the shorter arm carrying a stud adapted to be encountered by a releasing tumbler, to permit said 15 detent arm to engage the locking bolt when the key hub is turned, by the other keys, as hereinafter described.

In said figures; 1 is the locking bolt which is fitted to slide in the lock casing 2 having 20 the cover 3 removably secured by the screws 4 in threaded engagement with the sockets 5 in said casing. Said bolt 1 slides on the stationary stud shaft 6 which extends through 25 the slot 7 in said bolt, in rigid relation with said lock casing 2, and said bolt also slides on the stud shaft 9 which extends through 30 the slot 10 in said bolt and is carried by the change plate 12 which is fitted to slide in said casing 2 and has the abutment projection 13 adapted to abut against the auxiliary lock bolt 14 as indicated in Figs. IV, 35 V, VIII, and XXIII which prevents unauthorized change of the lock mechanism as aforesaid. The reciprocatory movement of 40 said change plate 12 and consequent shifting of said stud shaft 9, is limited by the extent of the space between the inner face of the right hand wall of the lock casing 2, as shown in Fig. IV, and the opposite edge of 45 the inwardly projecting rib 15 of said casing. Said change plate 12 is guided by the inwardly projecting bosses 16 and 17 on said casing 2; said boss 17 extending in the gating 18 of said plate so as to be encountered 50 by the shoulder 19 of said plate, when the latter is retracted and swung downwardly in the position for changing the tumblers, which is shown in Fig. VII; so that accidental displacement of said plate from that position is prevented.

The outward locking movement of said bolt 1 is limited by its stump 21 encountering the inner face of said casing 2 in the position shown in Figs. I, II, IV, V, VIII, XI and XXIII; and the inward unlocking movement thereof is limited by its right hand end encountering the opposite wall of said casing 2 as shown in Fig. VI. Said locking bolt 1 carries the stump 21 fitted to enter the gatings 22 of the fences 24 which are in fact sectoral gear wheels, as shown in Fig. IV, and are pivoted upon said stationary stud shaft 6. In the form of my invention shown, there are six of said fences 24 of precisely the same size and shape, each having

a sectoral series of ten gear teeth 25 adapted to respectively changeably engage the sectoral series of six gear teeth 27 upon respective tumblers 28 which are all of the same shape and pivoted upon said stud shaft 9, 70 which shaft, although normally stationary in said lock casing 2, in the position shown in Fig. IV, is carried by said change plate 12 so as to be shifted as aforesaid.

In order to prevent the interference of any of said fences or tumblers with adjoining fences or tumblers; I prefer to separate them by the partition plates 30 of which there are five in the form of my invention shown. Said plates 30 are all of the same 80 shape shown in Fig. XX, and have circular openings 31 fitting upon said stationary stud shaft 6, and also have slots 32 fitting upon said movable stud shaft 9. Each of said plates 30 has a notch 33 merely to afford 85 clearance for the movement of said bolt stump 21.

Said tumblers 28 are provided with respective springs 35 having their free ends bearing upon said casing 2 and tending to 90 thrust said tumblers downwardly, to the position shown in Figs. VII and XXII, when they are released from engagement with said fences. When in that position, the key sweep edges 36 of said tumblers 28 bear 95 upon the rotary key hub 39 which is journaled in said casing 2 and cover 3, as shown in Fig. IX. Said key hub 39 is provided with the cam 40, which turns in the recess 41 of said locking bolt 1 so as to shift the latter, back and forth, when said hub is turned. That is to say; said hub 39 may be turned to shift said locking bolt from the locked position shown in Fig. IV to the unlocked position shown in Fig. VI, while said 100 change plate 12 is prevented from moving from its normally stationary position shown in Fig. IV, by the auxiliary lock bolt 14. Said bolt 14 is mounted to slide, transversely to said locking bolt 1, between the guide 110 ribs 44 and 45 which project inwardly from said casing. However, the lock mechanism may be shifted to the abnormal position shown in Fig. VII only when said change 115 plate 12 is released for rearward movement by retraction of said auxiliary lock bolt 14 as shown in that figure.

Said hub 39 has two keyways 47 and 48, which are conveniently formed in diametrical alignment, as shown in Fig. I, and when 120 in registry with the respective notches 49 and 50 in the hub bearing 51 on said cover 3, said keyway 47 is adapted to receive the guard key 52 shown in Fig. XIII and said keyway 48 is adapted to receive main keys 125 such as the keys 53 and 54 respectively shown in Figs. XIV and XV.

Of course, said locking bolt 1 cannot be shifted as above contemplated, unless the main key inserted in said key hole 48 of 130

said hub 39 is bitted so as to sweep said tumblers 28 and the fences 24 connected therewith into such position as to hold all of said fences 24 with their gatings 22 in registry with said stump 21. Moreover, the guard lever 56, which is fulcrumed on the stud 57, which is in rigid relation with said casing 2, is provided with the spring 58 having its free end bearing upon said casing so as to normally present the detent arm 59 of said lever into engagement with the shoulder 60 on said locking bolt 1, to detain the latter in the locked position shown in Figs. I and IV, and means must be employed to release said guard lever 56 by manipulation of said guard key 52, as follows:

Said guard lever 56 has the stump 61 adapted to enter the gatings 62 of the guard tumblers 63 which are pivoted on the stud 64 which is in stationary relation with said casing 2, and said guard tumblers 63 are provided with respective springs 66 bearing at their free ends upon said casing 2 and tending to turn said tumblers upwardly into the position shown in Fig. IV in which position said tumblers 63 are stopped by their projections 67 encountering said stump 61. Said guard lever 56 has the arm 69 carrying the stud 70 which is adapted to be encountered by the releasing tumbler 71 which is also pivoted on said stationary stud 64 and provided with the spring 72 having its free end bearing upon said casing and tending to turn said releasing tumbler into the position shown in Fig. IV. It may be observed that when said guard lever 56 is turned into the position shown in Fig. V, its stud 70 is in position to be encountered by said releasing tumbler; so that said guard lever 56 may be released and restored to its normal position, (to detain said locking bolt 1 as shown in Fig. IV,) by downward movement of said releasing tumbler 71, when the latter is swept downwardly by said main key 53, turning said rotary hub 39.

Said guard key 52 and main key 53 are used to manipulate said lock, as follows:

The lock mechanism being in the position shown in Figs. I and IV; said guard key 52 is inserted in said keyway 47 in said hub 39 and the latter turned, clockwise, approximately, 60 degrees; the shape of said recess 41 in said locking bolt 1 being such as to permit such movement of the cam 40, without shifting said bolt 1. Said key 52 is bitted so as to sweep said tumblers 63 into position to receive said stump 61 in their gatings 62 and to then turn said guard lever 56 into the position shown in Fig. V, by the projecting bit 74 of said guard key 52, bearing upon the shoulder 75 of said guard lever 56. Thereupon, said hub 39 being returned to its normal position

shown in Figs. I and IV, and said guard key 52 being withdrawn, the lock is in position to be operated to retract said locking bolt 1 by the main key 53 shown in Fig. XIV. Said main key 53 being then inserted in the keyway 48 of said hub 39, the latter is turned, clockwise, approximately 120 degrees, from the normal locked position shown in Fig. IV to the normal unlocked position shown in Fig. VI. Said key 53 is bitted so as to sweep said tumblers 28 and their respective fences 24 into position to receive said stump 21 in the gatings 22 of said fences, thus permitting said cam 40, turning in said recess 41, to thrust said locking bolt 1 rearward to said unlocked position.

Reverse movement of said main key 53, effecting anticlockwise turning movement of said hub 39, suffices to return said locking bolt 1 to the locked position shown in Figs. I and IV, without any other manipulation of the lock mechanism.

However, when it is desired to change the lock mechanism to be operative by means of another main key; said auxiliary lock bolt 14 may be retracted by inserting the auxiliary lock key 77, shown in Fig. XVI, in the aforesaid guard keyway 47, and turning said hub 39 clockwise to the same extent that the guard key was turned, to wit, approximately 60 degrees; but only after said guard key has been manipulated, as above described. It may be observed that until the guard key 52 has been thus manipulated, the detent arm 59 of the guard lever 56 is engaged with the shoulder 60 on the locking bolt 1, as shown in Fig. IV; but such manipulation of the guard key 52 first sweeps said tumblers 63 into position to receive said stump 61 in their gatings 62 and then turns said guard lever 56 to disengage its detent arm 59 from said shoulder 60 of the locking bolt 1 and lowers said arm 59 to the position shown in Fig. V, thus permitting the further manipulation of the lock mechanism by said auxiliary lock key 77, as above contemplated. Said auxiliary slide bolt 14 is arranged to be reciprocated by means of the auxiliary lock lever 80 which is fulcrumed upon the stud 81 fixed in said casing and has the spring 82 having its left hand end, shown in Fig. IV, rigidly connected with said casing 2, and its right hand free end bearing upon the crank pin 83 projecting from said lever; and thus tending to thrust said lever upwardly to the position shown in Fig. IV. Said lever 80 carries the bell crank latch 85 which is hung upon the pivot pin 86 projecting from said lever 80. In the position shown in Fig. IV, said latch 85 is prevented from tilting in either direction by engagement with the lugs 87 on said casing 2 extending between its arms 89 and 90. Said arm

89 of said latch lever 85 is thus normally held in position to be engaged by the bit 92 at the end of the auxiliary lock key 77 shown in Fig. XVI, so that when said key 77 is inserted in the guard keyway 47 and turned as above described, said latch is turned, upon its pivot 86, from the position shown in Fig. IV to the position shown in Figs. VII and XXII, thus thrusting said lever 80 and auxiliary lock bolt 14 downwardly, to the position shown in Figs. VII and XXII, where they are held by the notch 91 in the arm 90 of said bell crank latch 85, engaging the corner of one casing lug 87 as shown in Figs. VII and XXII. Thereupon, said main key 53 may be manipulated as above described to shift said locking bolt 1 from the locked position shown in Fig. IV to the unlocked position shown in Fig. VI, but, by continuing the turning movement of said key 53, clockwise, to complete one-half revolution, instead of stopping when it has turned one-third revolution, as normally, when unlocking said bolt 1; said key 53, encountering the bearing 93 of said change plate 12, thrusts the latter to the position shown in Figs. VII and XXII, thus shifting said stud shaft 9 away from said stud shaft 6 and thereby disengaging the entire group of said main tumblers 28 from their respective fences 24, because said tumblers are pivoted upon said shaft 9 and carried with it. When the teeth 27 of said main tumblers 28 are thus disengaged from the teeth 25 of said fences 24, said tumblers are thrust downwardly, by their respective springs 35, into the position shown in Figs. VII and XXII, in which the key sweep edges 36 of said tumblers 28 bear upon said rotary key hub 39. Thereupon, said main keyway 48 being in registry with said notch 50 in the key hub bearing 51, said main key 53 may be withdrawn and the main key to which it is desired to adjust the lock mechanism may be inserted in said keyway 48, while the latter remains in the abnormal position last above described and which is shown in Figs. VII and XXII. For instance, the different main key 54, shown in Fig. XV, may be thus inserted and turned, anticlockwise, to first sweep said main tumblers upwardly into cooperative relation with the bits of said main key 54 and then carry them to the left, until the teeth 27 of said tumblers 28 are reengaged with the teeth 25 of said fences 24 but in the different position shown in Figs. VIII and XXIII. Such reengaging movement of said tumblers 28 is effected by said cam 40 on said key hub 39 thrusting against the left hand side of said recess 41 in said locking bolt 1 until the latter is restored to the locked position shown in Fig. IV, and as in Figs. VIII and XXIII; for, during the latter portion of

that locking movement, said main key encounters the bearing 94 of said change plate 12, best shown in Fig. XIX and carries the latter to the left, shifting it from the abnormal position shown in Figs. VII and XXII to the normal position shown in Figs. IV, VIII and XXIII. Thereupon, said auxiliary lock bolt 14 is automatically restored to its normal locked position shown in Fig. IV and as shown in Fig. VIII. As said locking bolt 1 thus passes to its locked position, it permits the detent arm of said lever 56 to rise into engagement with the bolt shoulder 60, under pressure of the spring 68 of said lever, because said shoulder 60 is then presented in its original forward position, shown in Fig. IV. Of course, when said detent arm 59 of the guard lever 56 is in its lowered, disengaged position aforesaid, the stud 70 on said guard lever 56 is in position to be encountered by the releasing tumbler 71, and the latter is swept downwardly by the key turning said rotary hub 39, so as to thus release said guard lever 56 and permit it to tilt to its original position shown in Fig. IV. Said lever 56 has the crank pin 96 which, in such movement of said lever, strikes the arm 89 of the latch 85, tilts said latch upon its pivot 86 so as to disengage its notch 91 from said lug 87 and permits the spring 82 of said lever 80 to uplift that lever and the auxiliary lock bolt 14 to its original locked position, shown in Figs. IV, VIII and XXIII. In other words; the first movement of the locking bolt 1 to its locked position, shown in Figs. IV, VIII and XXIII, after the tumbler changing mechanism has been utilized as above described, causes the auxiliary locking mechanism to automatically return to its normal locked position to prevent any further change in the combination of the lock until the above specified operation of the guard key 52 and change key 77 is effected in the manner above described.

It is to be understood that in the manner last described, said lock mechanism may be adjustably changed to cooperate with any one of a numerous series of different main keys, said keys differing from each other only in the arrangement of their bittings which cooperate with the main tumblers 28. Moreover, said lock mechanism is susceptible of much greater variation by changing the auxiliary lock tumblers 63 and, of course, providing auxiliary lock keys in accordance therewith, one such key, 97, being shown in Fig. XVII differing from the key 77 above described which is shown in Fig. XVI.

It is to be understood that said lock casing 2 is secured with its front face against the inner face of a door, or drawer front, by screws extending through the holes 98 in said casing; so that the front of the lock and said screws 4 which hold its cover 3

in position, are only accessible when the lock is bodily removed from its normal position.

It is to be understood that I do not desire to limit myself to the precise details of construction and arrangement herein set forth, as it is obvious that various modifications may be made therein without departing from the essential features of my 10 invention as defined in the appended claims.

I claim:

1. In a changeable combination key lock, the combination with a casing; of a locking bolt having a stump; a rotary key hub with 15 a main keyway and a guard keyway; main tumbler mechanism arranged to detain and release said bolt in accordance with the position thereof, including a series of counterpart pivoted main tumblers, each having a 20 sectoral series of gear teeth at its free end and each adjustable, at its free end, to change the combination; a series of counterpart rotary fences having respective sectoral series of gear teeth arranged to mesh with the 25 gear teeth on said respective main tumblers; each of said fences having a gating adapted to receive said locking bolt stump; a change plate, carrying said tumblers and movable in said casing to disengage said tumblers 30 from said fences and permit said tumblers to be changed; guard tumbler mechanism arranged to detain and release said bolt in accordance with the position thereof, including a guard lever having a detent arm 35 arranged to detachably engage said locking bolt, and having a portion adapted to be encountered by a guard key to disengage said detent arm from said locking bolt, and having a crank pin arranged to cooperate 40 with auxiliary lock mechanism, and a series of pivoted guard tumblers arranged to hold and release said guard lever in accordance with the position thereof, and controllable by said guard key; auxiliary lock mechanism, in said casing, including a reciprocating bolt adapted to normally prevent movement of said change plate, a lever fulcrumed in said casing, in cooperative relation with said auxiliary bolt, and a bell 45 crank latch pivoted to said auxiliary bolt lever and having one arm extending in position to be operated by an auxiliary key, inserted in said guard keyway, to unlock said auxiliary bolt and another arm adapted to engage said 50 casing and hold said auxiliary bolt in unlocked position, subject to automatic release by said crank pin; said auxiliary lock bolt being movable by said auxiliary key, to release said change plate and permit the tum- 55 ber combination to be changed; whereby a guard key and a main key are required to be successively inserted in the respective keyways in said hub to turn the latter to open the lock, and said main tumblers are pivoted to said change plate, to change the lock to be operated by different main keys.
2. In a changeable combination key lock, the combination with a casing; of a locking bolt; a rotary key hub with a main keyway and a guard keyway; main tumbler mechanism arranged to detain and release said bolt in accordance with the position thereof, including a series of pivoted main tumblers, each having a sectoral series of gear teeth at its free end and each adjustable, at its free end, to change the combination; a series of rotary fences having respective sectoral series of gear teeth arranged to mesh with the gear teeth on said respective main tumblers; a change plate, carrying said tumblers and movable in said casing to disengage said tumblers from said fences and permit said tumblers to be changed; guard tumbler mechanism arranged to detain and release said bolt in accordance with the position thereof, including a guard lever having a crank pin arranged to cooperate with auxiliary lock mechanism, and a guard tumbler arranged to hold and release said guard lever in accordance with the position thereof, and controllable by said guard key; auxiliary lock mechanism, in said casing, including a movable bolt adapted to normally prevent movement of said change plate, a lever in cooperative relation with said auxiliary bolt, a latch pivoted to said auxiliary bolt lever and extending in position to be operated by an auxiliary key, inserted in said guard keyway, to unlock said auxiliary bolt and another arm adapted to engage said casing and hold said auxiliary bolt in unlocked position, subject to automatic release by said crank pin; said auxiliary lock bolt being movable by said auxiliary key, to release said change plate and permit the tumbler combination to be changed; whereby a guard key and a main key are required to be successively inserted in the respective keyways in said hub to turn the latter to open the lock, and said main tumblers are pivoted to said change plate, to change the lock to be operated by different main keys.
3. In a changeable combination key lock, the combination with a casing; of a locking bolt; a rotary key hub with a main keyway and a guard keyway; main tumbler mechanism arranged to detain and release said bolt in accordance with the position thereof, including a series of pivoted main tumblers, each having a sectoral series of gear teeth at its free end and each adjustable, at its free end, to change the combination; a series of rotary fences having respective sectoral series of gear teeth arranged to mesh with the gear teeth on said respective main tumblers; a change plate, carrying said tumblers and movable in said casing to disengage said tumblers from said fences and permit said tumblers to be changed; guard tumbler mechanism arranged to detain and release said bolt in accordance with the position thereof, including a guard lever having a crank pin arranged to cooperate with auxiliary lock mechanism, and a guard tumbler arranged to hold and release said guard lever in accordance with the position thereof, and controllable by said guard key; auxiliary lock mechanism, in said casing, including a movable bolt adapted to normally prevent movement of said change plate, a lever in cooperative relation with said auxiliary bolt, a latch pivoted to said auxiliary bolt lever and extending in position to be operated by an auxiliary key, inserted in said guard keyway, to unlock said auxiliary bolt and another arm adapted to engage said casing and hold said auxiliary bolt in unlocked position, subject to automatic release by said crank pin; said auxiliary lock bolt being movable by said auxiliary key, to release said change plate and permit the tumbler combination to be changed; whereby a guard key and a main key are required to be successively inserted in the respective keyways in said hub to turn the latter to open the lock, and said main tumblers are pivoted to said change plate, to change the lock to be operated by different main keys.

with respect to said change plate, to change the lock, by manipulation of said auxiliary lock mechanism with an auxiliary lock key inserted in said guard keyway, to be operated by different main keys while subject to 70 operation by the same guard key.

2. In a changeable combination key lock, the combination with a casing; of a locking bolt; a rotary key hub with a main keyway and a guard keyway; main tumbler mechanism arranged to detain and release said bolt in accordance with the position thereof, including a series of pivoted main tumblers, each having a sectoral series of gear teeth at its free end and each adjustable, at its free end, to change the combination; a series of rotary fences having respective sectoral series of gear teeth arranged to mesh with the gear teeth on said respective main tumblers; a change plate, carrying said tumblers and movable in said casing to disengage said tumblers from said fences and permit said tumblers to be changed; guard tumbler mechanism arranged to detain and release said bolt in accordance with the position thereof, including a guard lever having a crank pin arranged to cooperate with auxiliary lock mechanism, and a guard tumbler arranged to hold and release said guard lever in accordance with the position thereof, and controllable by said guard key; auxiliary lock mechanism, in said casing, including a movable bolt adapted to normally prevent movement of said change plate, a lever in cooperative relation with said auxiliary bolt, a latch pivoted to said auxiliary bolt lever and extending in position to be operated by an auxiliary key, inserted in said guard keyway, to unlock said auxiliary bolt and another arm adapted to engage said casing and hold said auxiliary bolt in unlocked position, subject to automatic release by said crank pin; said auxiliary lock bolt being movable by said auxiliary key, to release said change plate and permit the tumbler combination to be changed; whereby a guard key and a main key are required to be successively inserted in the respective keyways in said hub to turn the latter to open the lock, and said main tumblers are pivoted to said change plate, to change the lock to be operated by different main keys.

3. In a changeable combination key lock, the combination with a casing; of a locking bolt; a rotary key hub with a main keyway and a guard keyway; main tumbler mechanism arranged to detain and release said bolt in accordance with the position thereof, including a series of pivoted main tumblers, each having a sectoral series of gear teeth at its free end and each adjustable, at its free end, to change the combination; a series of rotary fences having respective sectoral series of gear teeth arranged to mesh with the gear teeth on said respective main tumblers; a change plate, carrying said tumblers and movable in said casing to disengage said tumblers from said fences and permit said tumblers to be changed; guard tumbler mechanism arranged to detain and release said bolt in accordance with the position thereof, including a guard lever having a crank pin arranged to cooperate with auxiliary lock mechanism, and a guard tumbler arranged to hold and release said guard lever in accordance with the position thereof, and controllable by said guard key; auxiliary lock mechanism, in said casing, including a movable bolt adapted to normally prevent movement of said change plate, a lever in cooperative relation with said auxiliary bolt, a latch pivoted to said auxiliary bolt lever and extending in position to be operated by an auxiliary key, inserted in said guard keyway, to unlock said auxiliary bolt and another arm adapted to engage said casing and hold said auxiliary bolt in unlocked position, subject to automatic release by said crank pin; said auxiliary lock bolt being movable by said auxiliary key, to release said change plate and permit the tumbler combination to be changed; whereby a guard key and a main key are required to be successively inserted in the respective keyways in said hub to turn the latter to open the lock, and said main tumblers are pivoted to said change plate, to change the lock to be operated by different main keys.

- with the gear teeth on said respective main tumblers; a support for said tumblers, movable in said casing to disengage said tumblers from said fences and permit said tumblers to be changed; guard tumbler mechanism arranged to detain and release said bolt in accordance with the position thereof, including a crank arranged to cooperate with auxiliary lock mechanism, and controllable by a guard key; auxiliary lock mechanism, including a movable bolt adapted to normally prevent movement of said support, a lever in cooperative relation with said auxiliary bolt, a latch pivoted to said auxiliary bolt lever and extending in position to be operated by an auxiliary key to unlock said auxiliary bolt and adapted to hold said auxiliary bolt in unlocked position, subject to release by said crank pin; said auxiliary lock bolt being movable by an auxiliary key, to release said support and permit the tumbler combination to be changed; whereby a guard key and a main key are required to be successively inserted in the respective keyways in said hub to turn the latter to open the lock, and said main tumblers are pivotally adjustable with respect to said change plate, to change the lock to be operated by different main keys.
4. In a changeable combination key lock, the combination with a casing; of a locking bolt mounted to reciprocate in said casing; a tumbler mechanism arranged to detain and release said bolt in accordance with the position thereof and including a stud shaft laterally movable in said casing; a series of sectoral gear tumblers, pivoted on said shaft; a stud shaft stationary in said casing; a series of sectoral gear fences pivoted on said stationary shaft; a rotary key hub in operative relation with said bolt; auxiliary lock mechanism in said casing normally preventing disengagement of said tumblers from said fences; and means in said casing, arranged to be operated by an auxiliary lock key, inserted in said hub, to release said auxiliary lock mechanism and permit said tumblers to be disengaged from their fences to change the combination of said tumblers.
5. In a changeable combination key lock, the combination with a casing; of a locking bolt mounted to reciprocate in said casing; a tumbler mechanism arranged to detain and release said bolt in accordance with the position thereof and including a stud shaft laterally movable in said casing; a series of sectoral gear tumblers, pivoted on said shaft; a stud shaft stationary in said casing; a series of sectoral gear fences pivoted on said stationary shaft; a rotary key hub in operative relation with said bolt; auxiliary lock mechanism normally preventing disengagement of said tumbler from said fence; and means arranged to be operated by an auxiliary lock key, inserted in said hub, to release said auxiliary lock mechanism and permit said tumbler to be disengaged from said fence to change the relative position thereof.
6. In a changeable combination key lock, the combination with a casing; of a locking bolt movable in said casing; a tumbler mechanism arranged to detain and release said bolt in accordance with the position thereof and including a series of pivoted sectoral gear tumblers; a series of pivoted sectoral gear fences; a rotary key hub in operative relation with said bolt; auxiliary lock mechanism in said casing normally preventing disengagement of said tumblers from said fences; and means in said casing, arranged to be operated by an auxiliary lock key, inserted in said hub, to release said auxiliary lock mechanism and permit said tumblers to be disengaged from their fences to change the combination of said tumblers.
7. In a changeable combination key lock, the combination with a casing; of a locking bolt movable in said casing; a tumbler mechanism arranged to detain and release said bolt in accordance with the position thereof and including a series of pivoted sectoral gear tumblers; a series of pivoted sectoral gear fences; a rotary key hub in operative relation with said bolt; auxiliary lock mechanism in said casing normally preventing disengagement of said tumblers from said fences; and means in said casing, arranged to be operated by an auxiliary lock key, inserted in said hub, to release said auxiliary lock mechanism and permit said tumblers to be disengaged from their fences to change the combination of said tumblers.
8. In a changeable combination key lock, the combination with a casing; of a locking bolt mounted to reciprocate in said casing; a tumbler mechanism arranged to detain and release said bolt in accordance with the position thereof and including a stud shaft laterally movable in said casing; a rotary gear tumbler, pivoted on said shaft; a stud shaft stationary in said casing; a rotary gear fence pivoted on said stationary shaft; a rotary key hub in operative relation with said bolt; auxiliary lock mechanism normally preventing disengagement of said tumbler from said fence; and means arranged to be operated by an auxiliary lock key, inserted in said hub, to release said auxiliary lock mechanism and permit said tumbler to be disengaged from said fence to change the combination of said tumblers.
9. In a changeable combination key lock, the combination with a casing; of a locking bolt mounted to reciprocate in said casing; a tumbler mechanism arranged to detain and release said bolt in accordance with the position thereof and including a stud shaft laterally movable in said casing; a rotary gear tumbler, pivoted on said shaft; a stud shaft stationary in said casing; a rotary gear fence pivoted on said stationary shaft; a rotary key hub in operative relation with said bolt; auxiliary lock mechanism normally preventing disengagement of said tumbler from said fence; and means arranged to be operated by an auxiliary lock key, inserted in said hub, to release said auxiliary lock mechanism and permit said tumbler to be disengaged from said fence to change the combination of said tumblers.

gear fence pivoted on said stationary shaft; a rotary key hub in operative relation with said bolt; auxiliary lock mechanism normally preventing disengagement of said tumbler from said fence; and means arranged to be operated by an auxiliary lock key, to release said auxiliary lock mechanism and permit said tumbler to be disengaged from said fence to change the relative position thereof.

10. In a changeable combination key lock, the combination with a casing; of a locking bolt movable in said casing; a tumbler mechanism arranged to detain and release said bolt in accordance with the position thereof and including a rotary gear tumbler; a rotary gear fence; a rotary key hub in operative relation with said bolt; auxiliary lock mechanism in said casing normally preventing disengagement of said tumbler from said fence; and means in said casing, arranged to be operated by an auxiliary lock key, inserted in said hub, to release said auxiliary lock mechanism and permit said tumbler to be disengaged from said fence to change the relative position thereof.

11. In a changeable combination key lock, the combination with a casing; of a locking bolt movable in said casing; a tumbler mechanism arranged to detain and release said bolt in accordance with the position thereof and including a rotary gear tumbler; a rotary gear fence; a rotary key hub in operative relation with said bolt; auxiliary lock mechanism in said casing normally preventing disengagement of said tumbler from said fence; and means in said casing, arranged to be operated by an auxiliary lock key, to release said auxiliary lock mechanism and permit said tumbler to be disengaged from said fence to change the relative position thereof.

12. In a changeable combination key lock, the combination with a reciprocatory locking bolt; of tumbler mechanism arranged to detain and release said bolt in accordance with the position thereof; a rotary key hub having a main keyway and a guard keyway; a reciprocatory and oscillatory change plate, movable to change the combination of said tumbler mechanism; an auxiliary lock mechanism normally preventing movement of said change plate and including means operable by an auxiliary key inserted in said guard keyway to release said change plate; whereby a guard key and a main key are required to be successively inserted in the respective keyways in said key hub to unlock said locking bolt, and that guard key, an auxiliary key, and that main key, are required to be successively inserted in said key hub to permit change of the combination of said tumbler mechanism.

13. In a changeable combination lock, the

combination with a movable locking bolt; of tumbler mechanism arranged to detain and release said bolt in accordance with the position thereof; a rotary key hub having a main keyway and a guard keyway; a change element, movable to change the combination of said tumbler mechanism; an auxiliary lock mechanism normally preventing movement of said change element and including means operable by an auxiliary key inserted in said guard keyway to release said change element; whereby a guard key and a main key are required to be successively inserted in the respective keyways in said key hub to unlock said locking bolt, and that guard key, an auxiliary key, and that main key, are required to be successively inserted in said key hub to permit change of the combination of said tumbler mechanism.

14. In a changeable combination lock, the combination with a movable locking bolt; of tumbler mechanism arranged to detain and release said bolt in accordance with the position thereof; a rotary key hub; a change element, movable to change the combination of said tumbler mechanism; an auxiliary lock mechanism normally preventing movement of said change element and including means operable by an auxiliary key inserted in said key hub; whereby a guard key and a main key are required to be successively inserted in said key hub to unlock said locking bolt, and that guard key, an auxiliary key, and that main key are required to be successively inserted in said key hub to permit change of the combination of said tumbler mechanism.

15. In a changeable combination lock, the combination with a movable locking bolt; of tumbler mechanism arranged to detain and release said bolt in accordance with the position thereof; a rotary key hub; a change element, movable to change the combination of said tumbler mechanism; and an auxiliary lock mechanism normally preventing movement of said change element and including means operable by an auxiliary key inserted in said key hub.

16. In a changeable combination key lock, the combination with a casing; of a locking bolt; a rotary key hub with a main keyway and a guard keyway; a guard lever having a crank pin arranged to cooperate with auxiliary lock mechanism; a guard tumbler arranged to hold and release said guard lever in accordance with the position thereof, and controllable by a guard key inserted in said guard keyway; auxiliary lock mechanism in said casing, including a movable bolt, a lever in cooperative relation with said auxiliary bolt, and a latch pivoted to said auxiliary bolt lever, extending in position to be operated by a key inserted in said guard keyway, to unlock said auxiliary bolt,

and adapted to engage said casing and hold said auxiliary bolt in unlocked position, subject to automatic release by said crank pin.

17. In a changeable combination key lock, 5 the combination with a casing; of a locking bolt; a guard lever having a crank pin arranged to cooperate with auxiliary lock mechanism; a guard tumbler arranged to hold and release said guard lever in accordance 10 with the position thereof, and controllable by a key; auxiliary lock mechanism in said casing, including a movable bolt, a lever in cooperative relation with said auxiliary bolt; and a latch pivoted to said auxiliary bolt lever and extending in position to be operated to unlock said auxiliary bolt, and adapted to engage said casing and hold said auxiliary bolt in unlocked position, subject to automatic release by said crank pin.
18. In a changeable combination key lock, 20 the combination with a casing; of a locking bolt; a guard lever arranged to cooperate with auxiliary lock mechanism; a guard tumbler arranged to hold and release said guard lever in accordance with the position thereof, and controllable by a key; auxiliary lock mechanism in said casing, including a movable bolt, a lever in cooperative relation with said auxiliary bolt; and a latch extending 25 in position to be operated to unlock said auxiliary bolt, and adapted to hold said auxiliary bolt in unlocked position, subject to automatic release by said guard lever.
19. In a changeable combination key lock, 30 35 the combination with a casing; of a locking bolt; a guard lever arranged to cooperate

with auxiliary lock mechanism; a guard tumbler arranged to hold and release said guard lever in accordance with the position thereof, and controllable by a key; auxiliary lock mechanism in said casing, including a lever, and a latch pivoted to that auxiliary lever, extending in position to be unlocked, and adapted to hold said auxiliary lock mechanism in unlocked position. 40 45

20. In a changeable combination lock, the combination with a casing; of a movable locking bolt; a tumbler arranged to detain and release said bolt in accordance with the position thereof; a reciprocatory and oscillatory change plate, carrying said tumbler and movable to change the lock combination; an element stationary in said casing arranged to engage said change plate in one position of the latter; and means arranged 50 to oscillate and thus release said change plate. 55

21. In a lock, the combination with a movable bolt; of a lever operatively connected with said bolt; a latch pivoted on 60 said lever and arranged to detain said lever in unlocked position; and means arranged to release said latch and permit said bolt to be locked.

In testimony whereof, I have hereunto 65 signed my name at Philadelphia, Pennsylvania, this 5th day of March, 1920.

EDWARD WILLEY MARVEL.
